UNITED STATES PATENT OFFICE

KEIJIRO NISHIO, OF TOKYO, JAPAN

GEOLOGICAL SAMPLER

Application filed April 15, 1925, Serial No. 23,410, and in Japan April 16, 1924.

This invention relates to a geological sampler having an inner and an outer tube in which the former is axially halved and able to be readily put into the latter or taken apart therefrom in closed form, both tubes being 5 pressed into the ground or pulled out therefrom without being separated.

The object of the invention is to obtain a sample of continuous geological formation 10 without disorder or deformation by halving the inner tube, so that the investigation of the strata can be accurately performed.

In the accompanying drawings:

Fig. 1 is a longitudinal sectional elevation 15 of one embodiment,

Fig. 2 is a cross sectional view on the line A—B thereof,

Fig. 3 is a similar view on the line C—D thereof,

Fig. 4 is an elevation of a second embodiment partly in section,

Fig. 5 is a cross sectional view on the line E—F thereof,

Fig. 6 is a longitudinal sectional elevation 25 showing the application of the invention,

Fig. 7 is a cross section on the line G—H thereof,

Fig. 8 is an end view of a sampling inner tube, one half of which is removed after being taken out from an outer tube, and

Fig. 9 is a side elevation thereof.

Like numerals refer to like parts in the drawings.

The invention is fully described referring 35 to a few embodiments as follows:

The first embodiment shown in Fig. 1 consists of a head piece *a* which is provided with threads at its reduced portion 1 adapted for connection of a pressing in and taking out 40 device of any convenient form, said device being positioned at an upper level. The head piece is provided with threads at another reduced portion 2 which is further extended at 3 to form a flange portion having an annular groove 3a. Said groove is adapted for re-

ceiving a reduced end of axially halved inner tubes *C*₁ *C*₂ having serrations 6 at its extreme end. An outer tube *b* having a flared portion 4 is, after the inner tubes are attached to the head piece, to be screwed in the thread portion 2. 8 is a vent bored in the side walls of tubes *b* *C*₂. Therefore two tubes *b* *C*₁ *C*₂ can together be pressed into the ground or pulled out from it without being separated. 50

In the second embodiment shown in Fig. 2, 55 the head piece *a* is provided with a similar extension 1, however, lower extension 2 is rigidly attached to a sampling outer tube *b* by means of a transverse bolt 7. Sampling inner tubes *C*₁ *C*₂ are axially halved in the outer tube and the extreme ends of the two tubes are coincided. On the lower end of the outer tube *b*, a foot piece *d* is attached by means of threads 9, said foot piece being flared in a conical form from 10 where the foot piece is 60 engaged with the inner tube. Therefore the inner tubes *C*₁ *C*₂ can readily be taken out in closed form by removing the foot piece. 65

The manner of application of the samplers is the same in each case shown in Fig. 1 or 70 Fig. 2. A leading pipe *e* is driven into the ground and in this pipe the sampler (outer tube *b* and inner tubes *C*₁ *C*₂ in closed form) is inserted. The sampler is driven into the ground by any convenient means as shown in 75 Fig. 6 to a desired point where the outer and inner tubes *b* *C*₁ *C*₂ with the head piece *a* are pulled out from the ground. The inner tubes *C*₁ *C*₂ are removed in closed form from the outer tube *b*. One half, say, *C*₁ of the inner tubes is laid down horizontally and then another half is upwardly removed. (See Figs. 8 and 9.) 80

In this case, the sample in the inner tubes *C*₁ *C*₂ is more or less compressed so that it is 85 usually of less thickness than the actual thickness of the formation. Errors should be corrected by the following calculation. Then an accurate result may be obtained. 90

For example, assume

S = thickness of sample to obtain,
P = thickness of the earth to fall

5 down from the end of the
sampler,

D = depth of well at beginning of
each drilling operation,

D' = depth of well at finishing of
each drilling operation,

10 S' = actual thickness of sample,
then, $S' = D' - D - P$.

Assume, r = modulus of restratification

15 then, $r = \frac{S'}{S}$

Therefore, by multiplying this modulus by
every portion of sample, actual thickness can
be obtained.

20 The sample does not readily fall down be-
cause it is compressed by a device of conical
flare.

25 The invention is particularly adapted for
obtaining a sample in slushy or loose earth
crust, where a diamond or steel shot boring
machine may not be used.

I claim:

30 In a geological sampler, inner and outer
tubes, the inner tube being divided longitudi-
nally and composed of two separable parts,
an annular cutting edge at one end of the
outer tube adapted to penetrate the earth,
35 an internal shoulder constituting an abut-
ment for one end of the two-part inner tube,
a member threaded in the outer tube and
having a reduced portion extending within
and spaced from the wall of the outer tube
and provided with an annular groove, and
40 inwardly directed flanges on the parts of the
inner tube engaging said groove whereby the
inner tube may be withdrawn from the outer
tube upon axial displacement of said member
with respect to the outer tube, said means per-
mitting the separation of the parts of the
45 inner tube subsequent to removal of the latter
from the outer tube.

In testimony whereof he affixes his signa-
ture.

KEIJIRO NISHIO.
